CLAIM

The ornamental design for a sliding gate guide roller bracket, as shown and described.

DESCRIPTION

FIG. 1 is a perspective view of the sliding gate guide roller bracket of the present invention;

FIG. 2 is a side elevation view, the opposite side being a mirror image thereof;

FIG. 3 is a front elevation view thereof; and,

FIG. 4 is a top view, the bottom side view being identical thereof.

All portions of the drawing shown in dashed lines are for illustrative purposes only and form no part of the claimed design.
